UNITED STATES PATENT OFFICE.

CHARLES S. LEET, OF BRIDGEPORT, CONNECTICUT.

CALL-WHISTLE.

SPECIFICATION forming part of Letters Patent No. 250,083, dated November 29, 1881.

Application filed October 24, 1881. (No model.)

To all whom it may concern:

Be it known that I, CHARLES S. LEET, a citizen of the United States, residing at Bridgeport, in the county of Fairfield and State of Connecticut, have invented new and useful Improvements in Call-Whistles, of which the following is a specification.

This invention relates to the details of the construction of an improved call-whistle for 10 huntsmen and others, the object being to embody all the requisite elements of a whistle in the form of a complete metallic cartridge, and to so improve the construction thereof as to insure more effective operation of the twitter-ball usually inclosed in such whistles.

In the drawings forming part of this specification, Figure 1 is a side elevation of a call-whistle constructed according to my invention. Fig. 2 is a vertical section. Fig. 3 is a section 20 of the mouth-piece. Fig. 4 is an end view of the mouth-piece, looking toward the interior. Fig. 5 is an edge view of the air-diaphragm. Fig. 6 is a plan view of the same. Fig. 7 is an edge view of the frictional base-piece. Fig. 25 8 is a plan view of the same. Fig. 9 is a section of the whistle-body, and Fig. 10 illustrates the twitter-ball.

In the drawings, *c* is the whistle-case. *a* is the mouth-piece. *e* is the air-diaphragm. *v* is the frictional base-piece, and *x* is the twitter-ball.

The case or body of the whistle *c* is made of suitable metal or other material, in the well-known form of a metallic cartridge-shell, in one 35 side of which is formed the usual embouchure for the outward escape of air, and to the head thereof is secured a suspending-ring.

The mouth-piece *a* of the whistle is a short conical tube made in the form of a cartridge-ball, its point being perforated for the admission of air, and having around its body the usual lubricant-grooves.

The air-diaphragm *e* is of the usual form used in whistles.

45 A disk, *v*, is made of rubber, leather, or textile material, having a slightly-frictional surface; or it may be made of metal having its surface suitably roughened, and said disk is of such diameter as to make it retain its place

in the case *c* when crowded into it near the 50 head of the case, as in Fig. 2.

The twitter-ball *x* is, as usual, made of any light suitable material, such as wood, cork, &c.

The case *c* having been made as described and shown, the frictional disk *v* is inserted 55 therein, the ball *x* is next placed in the case above said disk, and the diaphragm is secured therein just above the said embouchure on its side. The said diaphragm *e* is made slightly tapering, the diameter of its face, toward the 60 head of case *c*, being greater than its upper or outer face, so that the lower edge of the mouth-piece *a* may enter between the upper part of its periphery and the case, in which manner the mouth-piece *a* is next applied to the case 65 *c*, and the edge of the latter around said diaphragm is crimped upon the lower end of the mouth-piece and diaphragm, thus securing said parts firmly together and completing the 70 whistle.

The frictional disk *v*, which is placed in the base of the case *c*, is an important feature in whistles of this class, as it serves to insure a constant bounding movement of the ball *x*, by which the essential twittering sound of the 75 whistle is produced, and without which said disk the ball will rest immovable. Rubber is the most preferable material from which to make said disks; but other suitable material 80 may be employed.

What I claim as my invention is—

1. As a new article of manufacture, a call-whistle consisting of a body or case, *c*, made in the form of a cartridge-shell, and of a hollow mouth-piece, *a*, made in the form of a cartridge-ball, said case and mouth-piece being combined to form a whistle having the form of a metallic cartridge, and provided with the diaphragm *e* and a suitable opening for the escape of air, substantially as set forth.

2. In a call-whistle, the disk *v*, constituting a frictional surface at the base of the case *c*, substantially as and for the purpose set forth.

CHARLES S. LEET.
